UNITED STATES PATENT OFFICE.

WILLIAM H. RAY, OF MONROE, MICHIGAN.

WINDOW-SCREEN CONSTRUCTION.

1,399,878.

Specification of Letters Patent. Patented Dec. 13, 1921.

Application filed February 28, 1919. Serial No. 279,813.

To all whom it may concern:

Be it known that I, WILLIAM H. RAY, of Monroe, Michigan, in the county of Monroe, in said State, have invented a certain new and useful Improvement in Window-Screen Construction, of which the following is a specification.

This invention relates to window screens, and more especially those which are adapted to be raised and lowered, or moved out of the window in some manner when not needed; and the improvement, in the specific application thereof hereinafter described, relates more particularly to the inclosed bodies of automobiles, and contemplates the provision in such a structure of window sashes which can be raised and lowered, as well as screens which can be raised and lowered, whereby the closed body is adapted for use in summer as well as in winter.

Generally stated, therefore, the object of the invention is to provide a novel and comparatively inexpensive and simple window construction of the foregoing general character, involving a sash which can be easily raised and lowered, and a screen which can be readily raised and lowered, and a means whereby both the sash and the screen can be stored out of the way when not in use.

It is also an object to provide certain details and features of construction tending to increase the general efficiency and desirability of a window sash and screen construction of this particular character.

To the foregoing and other useful ends the invention consists in matters herein set forth and claimed.

In the accompanying drawings—

Figure 1 is a vertical section of a portion of an automobile body, showing a sash and screen construction embodying the principles of the invention.

Fig. 2 is a perspective of the upper portion of the screen.

Fig. 3 is a view similar to Fig. 1, but showing the sash and the screen raised.

Fig. 4 is a horizontal section on line 4—4 in Fig. 1.

Fig. 5 is a vertical section on line 5—5 in Fig. 1.

Fig. 6 is a fragmentary perspective view of the lower portion of the window frame, and of the lower portions of the sash and screen.

Fig. 7 is a perspective of the upper portion of the sash.

Fig. 8 is an enlarged vertical section of the lower portions of the screen and sash, and adjacent portions of the window frame, and of the lock for the sash.

Fig. 9 is an inside front elevation of the said lock.

As thus illustrated, the automobile body comprises a side frame (1) of suitable character, and a top (2) that extends over the frame, it being understood that the body is thus provided with the usual or suitable openings in the frame. The under side of the top is provided with parallel guides (3), which extend horizontally in a direction at right angles to the plane of the upright frame (1), and similar guides (4) are provided immediately below said other guides, being preferably formed by sheet metal strips suitably bent to provide the grooves which form the guides.

The window sash (5) is of any suitable character, and is provided at its upper end with pivots (6) which engage the openings (7) when the sash is down, and which slide in the guides (3) when the sash is moved into its storage position under the top.

The screen (8) is of any suitable character, and has its upper end provided with pivots which slide in the guides (4) when the screen is raised and pushed horizontally into its storage position, but when the screen is down the pivots (9) then engage the recesses (10) in the frame. The side edges of the screen have strips of felt (11) which bear against the frame to make it tight, and similar strips (12) are provided on the side edges of the sash. The lower portion of the window frame has a ridge (13) which is engaged by the groove (14) in the lower edge of the screen when the latter is down. The lower portion of the window frame is also provided with a ledge (15) which is engaged by the catch (16) on the screen when the latter is down, and said catch occupies a notch of any suitable character (not shown) in the upper portion (17) of the frame when the screen is raised, so that the ring or handle (18) of the catch is in position to be employed to pull the screen outwardly and then downwardly into the window. The lower portion of the sash is provided with a lock to engage the recess (19) in the frame,

thereby to prevent the sash from swinging outwardly. This lock comprises a vertically movable member (20) which is made hollow to receive the cam (21) mounted on the transverse pivot (22), said member (20) having its upper portion provided with a ridge (23) which bears upon the top of the cam. Said cam has a handle (24) adapted to swing downwardly into the recess (25) formed in the member (20), and by this movement of the handle, said member is raised from the notch (19) in the frame, thereby unlocking the sash. When the sash is raised, and the handle swung into the recess (25), as shown in Fig. 3, said handle projects outwardly into position to be employed to pull the sash outwardly and then downward into the frame. Springs (26) are interposed between the top of the member (20) and the upper wall (27) of the sheet metal casing in which the mechanism of the lock is inclosed, whereby the member (20) is yieldingly held in its locking position.

Spring (28) are provided to bear upon the sash (5) when in raised or storage position, so that it will not rattle up and down. The top of the body has a lower wall (29) below the storage position of the sash and screen, which wall can be of any suitable material, whereby the sash and screen are concealed from view, and are practically inside of the structure of the top when in raised or storage position.

The weather strip (30) of any suitable material is preferably interposed between the ridge (13) and the inner side of the sash (5) to make a tight joint, and the strips (11) bear against the vertical stops (31) at the sides of the window frame when the screen is moved outwardly, and then swung downwardly to its position in the frame. The recesses (10) are so formed that the screen can be raised slightly when in lowered position, in order to disengage the groove (14) at its lower edge from the ridge (13), whereby the screen may then be swung outwardly and into a horizontal position in order to bring it into alignment with the guides (4) previously described.

From the foregoing it will be seen that when the sash (5) is down in place in the window frame, the body of the car will be closed, it being understood that all of the openings of the body are thus equipped with movable sashes. However, in summer time, the sashes can be raised and moved into their overhead storage positions in the top of the body, and the screens can then be pulled outward and downward into the opening or window frames of the body.

Of course, with the construction shown and described, the sash must be in raised position to permit the screen to be raised or lowered. When the screen is down, the sash can be pulled down from the outside.

If both the screen and the sash are down, then the screen can be raised slightly and swung inwardly, thereby affording access to the lock, so that the sash can be unlocked; and then the sash can be raised from the outside and moved into storage position in the top, leaving the screen down. Also, of course, the sash can be swung outward a little at the lower edge thereof, and held in this position by the handle (24), thus affording ventilation. The construction is such, it will be seen, that the screen 8 is manually releasable and operable entirely from within the automobile, and this is also true of the sash 5, for when the screen is in its storage position it is not necessary to go outside of the automobile to release the sash from its lowered position. In other words, when the sash is in raised position, the screen can be released and raised without the necessity of going outside of the automobile to manipulate any devices or parts of the structure, and when the screen is in raised position and the sash is down, the latter can be released and manually raised from within the automobile, as at such time no manipulation of any devices outside is necessary. Also, it will be seen that the top portion of the sash is in the plane of its horizontally disposed guides 3, 4, and that the top portion of the screen 8 is in the horizontally disposed plane of its guides 4, when the sash and screen are in their lowered positions. The top portion of the window frame preferably has a weather strip 32 against which the upper portion 33 of the sash bears, when the sash is in lowered or closed position, thereby to make the window dust and air tight at the top thereof. Thus, as stated, notwithstanding that the top portion of the sash is tightly closed when the sash is lowered, the sash can be raised without any manipulation of any parts outside. The screen is a sash, of course, as well as the outer sash in which the glass is carried, and thus either sash is adapted to be released and manually manipulated from the inside of the automobile in the manner explained.

In the combination of the glass window sash and the wire screen sash in one and the same window frame structure, with provisions for storing the two sashes in an overhead position, it will be seen that one sash is necessarily higher than the other. In the present case, inasmuch as the screen is stored below the glass window sash, it follows that the latter is desirably and necessarily of greater height than the screen.

What I claim as my invention is:—

1. In a convertible summer and winter top for an automobile, an upright frame, a top above said frame, inclosing means including a screen and comprising a movable sash which is higher than the screen for

said frame, and horizontally disposed guides extending over the upper end of the screen and disposed in position in said top to receive the sash, with the upper end of the 5 sash in the plane of said guides, whereby the sash may be swung outward at its lower end and then raised and moved horizontally over the screen and into an overhead storage position under the top, the sash being manually 10 releasable and operable in this manner entirely from within the automobile:

2. A structure as specified in claim 1, said screen being of less height than the sash, and means whereby said screen is movable 15 downwardly from the storage position thereof below the stored sash to a position in said frame, so that the sash and screen are adapted to be used interchangeably in said frame.

20 3. A structure as specified in claim 1, with the limitations of claim 2, having guides for the screen, all of said guides extending horizontally below the top, and the sash and screen having pivots that slide 25 in said guides and which permit either the sash or the screen to swing downward after being moved outwardly below said top.

4. A structure as specified in claim 1, with the limitations of claim 2, the screen being 30 movable from either position thereof only when the sash is in raised position, and means for retaining the lower edges of the sash and the screen in position when lowered into the frame.

35 5. A structure as specified in claim 1, in combination with a lock for the lower edge of the sash, having a swinging handle for operating said lock and which extends outward horizontally in the plane of the sash 40 from its position above to afford means for pulling the sash down into the frame.

6. The structure covered by claim 5, in which said lock has a locking element which is movable up and down in the lower portion 45 of the sash, and a cam operated by said handle to raise and lower said element, the lock being formed with clearance for permitting the handle to move into the position which it must assume to form the means for 50 pulling the sash downward into the frame.

7. In an automobile, a top extending overhead, a frame below the outer edge of the top, summer and winter inclosing means including a sash and a movable screen of different heights in said frame, so that the sash extends above the screen, and means whereby 55 said screen is manually releasable and operable entirely from within the automobile and is movable into a storage position under the top, and whereby the sash is movable into and out of said top.

8. In an automobile, the combination of a frame, an overhead top, a movable sash for said frame, a screen which is movable into 60 and out of the frame, the sash and screen

being of different heights and means whereby the sash is manually releasable and controllable entirely from within the automobile and is adapted to be raised into a storage position under the top.

70

9. In window construction, the combination of a sash, means whereby said sash is movable upwardly into an overhead position for storage, a screen of less height than the sash for the window, and means whereby 75 said screen has an overhead storage position and is movable downwardly therefrom after the sash is raised, both the sash and the screen being manually releasable and controllable entirely from the inside thereof.

80

10. A structure as specified in claim 9, said means comprising guides for holding the screen and sash horizontally, one below the other, and pivots on said sash and screen to engage said guides, in combination with devices to lock the lower edges of the sash and screen in place when lowered from the storage position thereof.

85

11. A structure as specified in claim 7, said sash being movable upwardly into a storage 90 position in the top, a lock for the lower portion of said sash, said lock having an operating handle which extends upwardly between the sash and screen, when the sash and screen are both down, and which extends outward from its upper position to form a handle for raising and lowering the sash, said screen when lowered being movable inwardly a distance at its lower edge to afford access to said handle.

100

12. The structure covered by claim 5, said handle being adapted to extend upwardly between the sash and screen, when both the sash and the screen are in lowered position, and to extend outwardly at the top of the 105 frame when the sash is in the storage position thereof.

13. In an automobile, an upright frame, a top above said frame, a movable sash disposed in said frame, and guides in said top 110 to receive the sash, so that the sash may be raised and stored in an overhead position under the top, in combination with a screen of less height than the sash, and means whereby said screen is movable downwardly 115 from the storage position thereof below the stored sash to a position in said frame, so that the sash and screen are adapted to be used interchangeably in said frame.

14. In an automobile, an upright frame, 120 a top above said frame, a movable sash disposed in said frame, and guides in said top to receive the sash, so that the sash may be raised and stored in an overhead position under the top, in combination, with a screen 125 of less height than the sash, and means whereby said screen is movable downwardly from the storage position thereof below the stored sash to a position in said frame, so that the sash and screen are adapted to be 130

used interchangeably in said frame, having guides for the screen, all of said guides extending horizontally below the top, and the sash and screen having pivots that slide in said guides and which permit either the sash or the screen to swing downward after being moved outwardly below said top.

15. In an automobile, an upright frame, a top above said frame, a movable sash disposed in said frame, and guides in said top to receive the sash, so that the sash may be raised and stored in an overhead position under the top, in combination with a screen of less height than the sash, and means whereby said screen is movable downwardly from the storage position thereof below the stored sash to a position in said frame, so that the sash and screen are adapted to be used interchangeably in said frame, the 20 screen being movable from either position thereof only when the sash is in raised position, and means for retaining the lower

edges of the sash and the screen in position when lowered into the frame.

16. In an automobile, an upright frame, a top above said frame, a movable sash disposed in said frame, and guides in said top to receive the sash, so that the sash may be raised and stored in an overhead position under the top, in combination with a lock 25 for the lower edge of the sash, having a swinging handle for operating said lock and to afford means for pulling the sash down into the frame, said lock having a locking element which is movable up and 30 down in the lower portion of the sash, and a cam operated by said handle to raise and lower said element, the lock being formed with clearance for permitting the handle to move into the position which it must assume to form the means for pulling the sash 35 downward into the frame.

WILLIAM H. RAY.
